(74) Attorney, Agent, or Firm — Miller Law Group,
 PLLC(57) **CLAIM**

The ornamental design for a roadside hazard flag, as shown and described.

DESCRIPTION

FIG. 1 is a front view of a roadside hazard flag in an assembled configuration showing my new design;
 FIG. 2 is a back view thereof;
 FIG. 3 is a right side perspective view thereof;
 FIG. 4 is a left side perspective view thereof;
 FIG. 5 is a front view of the roadside hazard flag laid flat;
 and,
 FIG. 6 is a back view of the roadside hazard flag laid flat. The broken lines in the drawings depict stitching that form a part of the claimed design.
